(57) **CLAIM**

The ornamental design for an LED lead frame as shown and described.

DESCRIPTION

FIG. 1 is a perspective view of an LED lead frame showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side view thereof; and,

FIG. 7 is a right side view thereof.

The dash-dash broken lines illustrate portions of the LED lead frame which form no part of the claimed design.

The dash-dot-dash-dot broken lines are boundary lines and define the bounds of the claimed design. The claimed design extends to the boundary lines but does not include the boundary lines.
